UNITED STATES PATENT OFFICE.

HUGH DAVID WALKER, OF PRESTON, CANADA.

DESIGN FOR A STOVEPIPE-THIMBLE.

SPECIFICATION forming part of Design No. 29,102, dated July 26, 1898.

Application filed April 21, 1898. Serial No. 678,400. Term of patent 7 years.

To all whom it may concern:

Be it known that I, HUGH DAVID WALKER, a subject of the Queen of Great Britain, and a resident of the town of Preston, in the county 5 of Waterloo, in the Province of Ontario, Canada, have invented and produced a new and original Design for a Stovepipe-Thimble, of which the following is a specification, reference being had to the accompanying drawings, forming part thereof.

Figure 1 is an elevation, and Fig. 2 is a plan view. Fig. 3 is a vertical section through the thimble.

The leading feature of my design consists 15 of a stovepipe-thimble having a corrugated body, an outwardly-extending flange at one end of the corrugation, and an inwardly-ex-

tending flange having perforations extending through the same.

As shown, the thimble has a corrugated body portion C and an inwardly-extending rim A, slightly tapering, and this rim, as shown in Fig. 2, has a series of holes through it. Projecting from the periphery of the thimble a little below the position of the rim A is 20 an outwardly-extending flange B.

What I claim is—

The design for a stovepipe-thimble herein shown and described.

HUGH DAVID WALKER.
